FILM MOUNTING DEVICE

Donald J. Albert, Rochester, and Edward W. Forman, Palmyra, N.Y., assignors to Eastman Kodak Company, Rochester, N.Y., a corporation of New Jersey

Filed May 22, 1961, Ser. No. 111,819

12 Claims. (Cl. 156—367)

The present invention relates to apparatus for mounting a piece of film in a card provided with an aperture and more particularly to apparatus which automatically withdraws a piece of film from a stack, locates the film in the card aperture and secures the film against adhesive strips carried by the card.

Apparatus of various types for mounting a piece of film within a card aperture and in contact with an adhesive frame secured to the card and over the aperture is well known. Such apparatus is very complicated in that it requires the removal of a cover sheet from the exposed adhesive surface of the frame within the card aperture as well as an optical system for registering the film with the aperture. Usually, the problem of registry is of extreme importance because the piece of film to be mounted in the card aperture must first be severed from a strip of film and then moved into and mounted in the card aperture. Since microfilm is not usually perforated, the advancement of the filmstrip cannot be accurately controlled. In addition, the spacing between successive images on the film is not uniform so it becomes necessary to register each image with the card aperture before severing it from the strip.

In the present invention, the pieces of film are precut to the required size and stacked in a receptacle arranged over a mounting station. The card has a preformed aperture of the required size and shape and two spaced strips of adhesive material are secured to opposite sides of the card aperture, the portion of the strip within the card aperture being used to hold the piece of film positioned in the aperture. The card with the adhesive surfaces facing the receptacle is positioned under the receptacle and when so positioned initiates a cycle of operation which includes movement of a plunger through the aperture in the card and into engagement with the lowermost piece of film in the stack, applying a vacuum to the plunger for withdrawing the piece of film from the receptacle, reversing the movement of the plunger to withdraw the film and position it in the card aperture against the strips of adhesive material and actuating a set of spaced rollers for engaging the film to roll it into intimate contact with the adhesive strips. The card is then withdrawn and the cycle is again initiated by another card. With this arrangement, the operator is merely concerned with insertion and withdrawal of the card and no registry of the film with the card aperture or severing of the film from a strip is required. In this way the apparatus is simpler in structure and eliminates the necessity for complicated cutting dies which, as used in the prior art, cut not only the film but also the card aperture.

The primary object of the invention is, therefore, to provide a device for mounting a piece of film in a card aperture which performs a complete mounting cycle of operation upon insertion of a card into the device.

Another object of the invention is to provide a device for mounting a piece of film in a card aperture in which the film is withdrawn from a stack by a vacuum plunger and positioned in the aperture.

Still another object of the invention is to provide a device for mounting a piece of film in a card aperture having at least two spaced adhesive strips extending thereacross and secured to the card and against which the film is positioned for retention in the aperture.

2

And yet another object of the invention is to provide a device for mounting a piece of film in a card aperture in which the film, after being positioned in the aperture, is rolled into intimate contact with spaced adhesive strips arranged across the card aperture.

These and other objects and advantages will be apparent to those skilled in the art by the following description of an embodiment of the invention;

Reference is now made to the accompanying drawings 10 wherein like reference numerals and characters designate like parts and wherein:

FIG. 1 is a plan view of a card showing the spaced adhesive strips overlying the card aperture and the piece of film arranged in the aperture and secured to the strips;

FIG. 2 is a vertical section through the card taken substantially along line 2—2 in FIG. 1;

FIG. 3 is a plan view of the mounting device showing the relationship of the mechanical, hydraulic and electrical components;

FIG. 4 is a partial vertical section taken substantially along the line 4—4 in FIG. 3;

FIG. 5 is a detail sectional view of the plunger for withdrawing a piece of film from the receptacle; and

FIG. 6 is a schematic wiring diagram showing the inter-relationship of the hydraulic and electrical components of the device.

With reference to FIGS. 1 and 2, card 10 can be of any desired size depending on the intended use of the card. In the present instance, the card is 3 1/4 inches wide and 5 inches long and is provided with an aperture 11 arranged at one end of the card. By means, which forms no part of the present invention, adhesive strips 12 are secured to the card and arranged in spaced relationship with respect to the aperture as shown in FIG. 1. It will be noted that the strips overlie a portion of the aperture at each end thereof and the piece of film, indicated by the numeral 13, lies within the aperture 11 and is secured at its ends to the spaced adhesive strips 12. The pieces of film 13 are precut to the desired size and shape and are provided at one end with an elongated slot or aperture 14. The aperture 14 is utilized for handling the film in various machine processes by means of a file stick which is inserted through the aperture to retain a plurality of such pieces of film on the stick for handling as a unit.

With reference to FIGS. 3 and 4, a base plate 20 carries the structure comprising the mounting device. This base plate carries a vertical plate 21, a second and narrower vertical plate 22, and a plate 23 which extends between the two first-mentioned plates to tie them together and to provide a support for the receptacle 24. As shown in FIG. 4, the receptacle 24 is mounted between a set of brackets 25 which are mounted on the horizontal plate 23. The receptacle 24 is pivotally mounted at 26 to the brackets 25 and is maintained in a vertical and aligned position with respect to mounting station 30 by the adjustable stop 27. The receptacle 24 is an open-end receptacle which permits the pieces of film to be loaded from the top and to be withdrawn from the bottom in a manner to be described hereinafter. At the bottom of receptacle 24 an L-shaped member 28 is secured to opposite sides of the receptacle, the horizontally extending legs thereof forming ledges which extend into the bottom open end of the receptacle for retaining the pieces of film in stacked and superimposed relation. The ledges are angled to impart a twist to the piece of film as it is withdrawn by the plunger 40 to separate this piece from the piece immediately above thereby preventing the extraction of more than one piece of film due to contact vacuum between the pieces of film. Upon movement 55 of the receptacle 24 in a counterclockwise direction about its pivot 26, the mounting station 30 is cleared to permit

60 At the bottom of receptacle 24 an L-shaped member 28 is secured to opposite sides of the receptacle, the horizontally extending legs thereof forming ledges which extend into the bottom open end of the receptacle for retaining the pieces of film in stacked and superimposed relation. The ledges are angled to impart a twist to the piece of film as it is withdrawn by the plunger 40 to separate this piece from the piece immediately above thereby preventing the extraction of more than one piece of film due to contact vacuum between the pieces of film. Upon movement 65 of the receptacle 24 in a counterclockwise direction about its pivot 26, the mounting station 30 is cleared to permit

removal of any card which may have become jammed therein, to permit access to the plunger 40, or to remove the retainer from the end of the stick described above to permit withdrawal of the stick after the pieces of film have been loaded into the receptacle 24.

The mounting station 30 comprises a plate 31 having an aperture 32 which is aligned with the open end at the bottom of receptacle 24. Plate 31 is carried by the vertical plate 21 and the vertical plate 33. The end of plate 33 is also secured to the edge of plate 22 as shown in FIG. 3. The front edge of plate 20 carries a vertical plate 34 which is secured at one end to the vertical plate 21. At the upper end of plate 34, spring guides 35 are mounted to the rear surface of the plate and at the end thereof carry the spaced leaf springs 36. The plate 31 is also provided with spaced edge guides 37 for guiding the card into proper relationship with respect to aperture 32, one of the edge guides 37 being spring biased to hold and position the card against the other edge guide. The plate 34 is provided with a horizontal slot 38 which is slightly longer than the width of the card to permit movement of the card through the slot and into engagement with the leaf springs 36 and the edge guides 37. These members position the card and hold it against the plate 31 as it is moved inward toward the rear end of plate 31 where the edge of the card engages the arm of the microswitch S4 for a purpose to be described hereinafter.

Immediately below aperture 32 in plate 31, a reciprocating plunger 40 is arranged between the blocks 41 and 42 which are carried by the vertical plate 33. The block 41 is secured to plate 33 and is provided with a recess in which the stem 43 of plunger 40 moves. The stem 43 of plunger 40 is provided with a vertical hole 44 which meets a horizontal hole 45 to connect the head 46 of the plunger to a vacuum port 47 in the block 42. The stem 43 also carries a pin 48 which extends through slots 49 in the side walls of block 41, the slots serving to limit the movement of plunger 40 in a vertical direction. A rod 50 is also retained between blocks 41 and 42 in the same manner as stem 43, the upper end abutting the end of stem 43 within said blocks and the lower end being pivotally mounted at 51 to the rocker arm 52. Rod 50 also carries a pin 53 which extends through the rod and, on each side, pin 53 is connected to pin 48 by suitable coil springs 80. Rocker arm 52 is connected to shaft 55 for movement therewith, being journaled in the spaced blocks 56. The other end of shaft 55 is journaled in plate 21 and between the inner block 56 and the inner wall of plate 21, three cams 57, 58, and 59 are secured to said shaft for movement therewith. Each of cams 57, 58 and 59 is provided with a cam surface at the end thereof as shown in FIG. 4. These cam surfaces actuate, respectively, the microswitches S5, S6 and S7 shown in FIG. 4. The rocker arm 52 is provided with an extension 60 which is fixed thereto to form, in effect, a bell crank lever which rotates or oscillates shaft 55 in a manner to be described.

Between the shaft 55 and the end of rocker arm 52, a bracket 63 is provided which serves as a mount for a U-shaped arm 64. The U-shaped arm is secured to shaft 65 which is rotatably mounted in bracket 63 and the leg 66 of arm 64 engages the pin 53 which is carried by rod 50. Arm 64, because of its shape and the manner in which it is mounted with respect to shaft 65, lies against a stop 67 and at this end carries a flexible leg 68 at the end of which are rotatably mounted the spaced rollers 69 and 70. From the description thus far, it should be evident that as rocker arm 52 moves in a clockwise direction, the rod 50 is moved vertically downward and the pin 53 engages the leg 66 to move the arm 64 and the shaft 65 thereby moving rollers 69 and 70 over the mounting station 30.

The means for actuating the rocker arm 52 and, hence, the plunger 40 comprises a vacuum cylinder 75 which is

a commercially available item. The piston rod 76, which extends from cylinder 75, is connected at its end to the extension 60 of rocker arm 52 at 77. As the rod is moved to the left, the rocker arm 52 will then be moved in a counterclockwise direction to move the plunger 40 vertically upward and when moved to the right will move the rocker arm 52 in a clockwise direction to move the plunger 40 in a vertically downward direction, as described more fully hereinafter.

With respect to FIG. 3, a vacuum supply is connected to pipe 89 and this line is connected to the electrically operated valves L3, L2 and L4 respectively, a vacuum switch S11 being in the line 80 between the valve L2 and the valve L4. The valve L3 is connected to the bottom and front side of the vacuum cylinder 75 for controlling the movement of the piston therein to the right or, in other words, the downward movement of plunger 40. Valve L2 is connected to the left-hand side of cylinder 75 and, hence, controls the movement of rocker arm 52 for moving the plunger 40 in a vertically upward direction. The valve L4 controls the application of the vacuum to the plunger 40. The valve L4 is, therefore, connected to the vacuum port 47 in the block 42 by the line 85 and this vacuum through the holes 45 and 44 provides a vacuum at the head of the plunger 40. As will be described more fully hereinafter, the valves L2, L3 and L4 control the application of the vacuum to the vacuum cylinder 75 and the plunger 40 so a complete cycle of operation is obtained. This will be more readily understood when the mechanical structure described thus far is combined with the wiring diagram shown in FIG. 6.

At the start of a cycle of operation, the various mechanical and electrical components will be in the positions shown in FIGS. 4-6. With reference particularly to FIG. 6, the switch S2 is normally closed and the switch S1 is normally open. To start the device, the switch S1 is closed and by this action the relay K1 is energized. With the energization of relay K1, its contact K1-1 is closed and the relay is therefore held in through the switch S2. At the same time, contact K1-2 is closed and contact K1-3 is opened thereby providing a reduced voltage, due to the transformer T, to the indicator lamps D3 and D4 by virtue of the closing of contact K1-2 and opening of the circuit to D5 and D6 by virtue of the opening of contact K1-3. With the energization of relay K1, its contact K1-4 is also closed and this places the vacuum motor M across the lines to provide the necessary vacuum to the device.

At this point, a card is inserted through the aperture 33 in the plate 34 and moved to the left until it engages the arm of switch S4, the card being guided by the edge guides 37 and being held against plate 31 by the leaf springs 36. The card is inserted with the strips 12 against the plate 31, see FIG. 5, so the exposed adhesive surfaces 55 of the strips face upward and toward the receptacle 24. With the closure of switch S4 by the edge of the card, relay K3 is energized through the closed contact of relay K4-1. The contact K3-1 is then closed and holds in the relay K3 by virtue of the relay contact K7-1 which is closed. Contact K3-2 is caused to switch so a circuit is completed across the lines to energize the valve L2 and thereby open the valve. At the same time contact K3-3 is closed to energize the indicator lights D1 and D2 which show the operator that the mounting cycle has commenced. With the energization of valve L2 the left-hand side of cylinder 75 is connected to the vacuum supply and the piston therein is therefore caused to move to the left. When this occurs, the rod 76 moves in the same direction and due to this movement the rocker arm 52 and the shaft 55 are rotated in a counterclockwise direction. This movement causes rod 50 to be moved vertically upward and since rod 50 is in abutting engagement with the end of stem 43, the plunger 40 is also moved in a vertically upward direction until the pin 48 engages the upper extremity 75 of the slots 49. As shaft 55 is rotated by the rocker arm,

the cams 57, 58 and 59 are moved therewith and in the course of their movements in either the clockwise or counterclockwise direction, actuate their respective switches S5, S6, and S7. At the normal position, that is, when the plunger 40 is immediately below the card level, as shown in FIGS. 4 and 5, cam 58 has actuated its respective switch S6 to a closed position and this is the normal position in FIG. 6. As a result, as soon as the plunger 40 is moved in an upward direction, the cam 58 releases switch S6 and this switch then assumes an open position, the switches S5 and S7 not being actuated on this vertically upward movement. However, once the plunger 40 has moved to its uppermost position in which it is in engagement with the lowermost piece of film in the receptacle 24, the cam 57 then causes the switch S5 to move to its other contact. When this occurs, relay K5 is energized by virtue of the closed contact K6-1 of relay K6. With the energization of relay K5, its contact K5-1 closes to hold this relay in through switch S7, its contact K5-2 closes to energize the vacuum valve L4, the contact K5-3 closes to energize relay K4, and the contact K5-4 closes to hold in the lamps D1 and D2. With the energization of relay K4, its contact K4-1 transfers and thereby isolates relay K3 from switch S4. At the same time that K5 is energized, relay K7 is also energized, the relay K7 having a time delay which permits the contacts of relay K5 to change their state before the relay K7 becomes effective. The delay of relay K7 also permits the plunger 40 to be held against the lowermost piece of film as the vacuum is applied to insure that the piece of film will be withdrawn when the direction of movement of the plunger is reversed. With the energization of relay K7, its contact K7-1 opens which releases the relay K3 and its contact K7-2 closes to energize the valve L3. Since L4 was energized with the closure of switch S5, the effect of the vacuum has had an opportunity to cause engagement of the lowermost piece of film before the energization of L3 takes effect to reverse the movement of plunger 40. With the de-energization of relay K3, of course, the valve L2 is de-energized and the contact K3-3 is open but the indicator lamps D1 and D2 are maintained in an energized condition due to the closure of the contact K5-4.

With the application of the vacuum to the right-hand side of cylinder 75, the piston is moved to the right thereby causing the rocker arm 52 and shaft 55 to be rotated in a clockwise direction. As the plunger 40 starts its downward movement and carries the piece of film therewith past the ends of the L-shaped members 28, the switch S5 returns to its initial position due to the movement of its cam 57 and the circuit through K7 is then actually maintained through S7 and the contact K5-1. The switch S11 which is located in the line 80 ahead of the valve L4 is a commercially available switch which is actuated by the vacuum. As a result, when a piece of film is carried by the plunger 40, the switch S11 is actuated and held in an open position. However, if the receptacle 24 is empty and the plunger does not pick up a piece of film, the loss of the vacuum will cause the switch S11 to close. In the description thus far it has been assumed that the plunger 40 has picked up a piece of film and is withdrawing it toward the plate 31 and the card 10 in the mounting station and, in this case, the switch S11 will therefore be in an open position. As the plunger passes through the intermediate or normal position, it will come to rest due to the engagement of the pin 48 with the lower extremity of the slots 49 in block 41. At this precise time, the switch S6 will again be actuated to a closed position but due to the fact that S11 is open the relay K6 will not be energized. As a result, the rocker arm 52 and shaft 55 are moved still further in a clockwise direction. At this normal or intermediate position, the pin 53 will engage the leg 66 of the arm 64 and, as rod 50 moves vertically downward, will cause arm 64 to move in a clockwise direction to move the rollers 69 and 70 over the edges of the film so as to press the film into intimate contact with the

areas of the adhesive strips exposed within the aperture 11 of the card 10. Since the movement of the plunger 40 is inhibited by the pin 48 engaging the lower end of its slot, the springs 80 connecting pins 48 and 53 are extended as the rod 50 is moved downward and the rollers 69 and 70 are moved through the mounting station. At the extremity of the downward movement of rod 50 by rocker arm 52, the cam 59 actuates the switch S7 to break the circuit through relay K5 and energize the relay M1 which is associated with an electromagnetic counter, not shown. With the de-energization of relay K5, its contact K5-1 opens to insure that the relay cannot be held in, the contact K5-2 opens to de-energize valve L3 and therefore cut off the vacuum to cylinder 75 and stop further movement of rod 50 and the contact K5-3 in the circuit of relay K4 opens but since K4 is energized and held in by the card switch S4 and its contact K4-1, the relay K4 remains energized until the card is withdrawn from the mounting station. The contact K5-4 also opens with the de-energization of relay K5 and the lamps D1 and D2 are therefore de-energized to indicate that the mounting cycle has been completed. The operator then withdraws the card from the mounting station and when this occurs the switch S4 opens thereby de-energizing relay K4 and returning the circuits to their normal condition for the start of another cycle by insertion of a card into the mounting station 30. When the vacuum is cut off from the cylinder 75 by de-energization of the valve L3, the springs 80 move the rod 50 as well as the rocker arm 52 into the normal or intermediate position and with the vertical movement of the rod 50 into abutting relation with the end of stem 43, the U-shaped arm 64 is also returned to its normal position against the stop 67, as shown in FIG. 4.

In the event the cycle of operation has proceeded to the point where a plunger fails to pick up a piece of film, the fact that the film is not over the plunger is detected by the switch S11 which then assumes its closed position. As the plunger 40 is moved vertically downward and assumes the normal or intermediate position, the switch S6 is actuated to a closed position by the cam 58 as already described. When this occurs, a circuit is completed through contact K5-2, switch S6, and switch S11 to energize relay K6. With the energization of relay K6, its contact K6-1 is opened thereby de-energizing relay K5 and its contact K6-2 is closed to energize relay K2 which is then held in by the closing of its contact K2-1. At the same time the contact K2-2 is closed to provide a circuit through the indicator 81 which signifies to the operator that the receptacle 24 no longer contains any pieces of film. With the de-energization of relay K5, its contact K5-2 opens to de-energize the valve L3 thereby preventing any further movement of the plunger 40 and at the same time de-energizing the valve L4 to shut off the vacuum to the plunger 40.

With the de-energization of relay K5 by the opening of the contact K6-1, the contact K5-2 is then open and the circuit to relay K6 is also open thereby dropping out this relay, relay K2 being held in by its contact K2-1. Since the contact K5-1 also reverts to its open position, the relay K7 is also de-energized. As a result, relays K4 and K2 remain energized, K4 because it is held by its contact K4-1 and the card in the mounting station which holds the switch S4 in its closed position and K2 because it is held in by its contact K2-1 for maintaining its contact K2-2 closed to maintain lamp 81 energized for indicating "no film." In order to initiate a further cycle of operation therefore, it is necessary for the operator to withdraw the card from the mounting station, thereby permitting switch S4 to open and de-energize relay K4 so its contact K4-1 returns to its normal position on the side toward relay K3. A stack of film can then be inserted into the receptacle 24 and the card reinserted in the mounting station to then initiate a cycle of operation which will be repeated with the insertion of each new card so long as the receptacle 24 is supplied with pieces of film.

It should be pointed out that the U-shaped arm 64 is designed so that the rollers 69 and 70 on the end of the leg 68 are biased toward the film as the arm is moved into the mounting station. This is necessary to obtain a roll-down action or pressure on the film to insure intimate contact of the film with the portions of the adhesive strips within the card aperture. For this reason the leg 68 is made of a relatively thin and flexible material to permit flexure of this leg as it is moved over and through the mounting station. In the extreme position to the right, the rollers 69 and 70 assume a position just beyond the right-hand edge of the piece of film in the mounting station. At this point, the position of the U-shaped arm 64 is such that its center of gravity is still to the left of the shaft 65, so that upon release of the pin 53 from the leg 66 the arm 64 falls toward the stop 67 due to its own weight and therefore follows the pin 53 upward till it assumes its normal or intermediate position in which the upper end of rod 50 abuts the lower end of stem 43.

The head of plunger 40 can be provided with a rubber pad which is substantially resilient and yieldable and which is provided with a number of apertures to provide maximum vacuum effect when engaging the lowermost piece of film in the receptacle 24. A similar plunger head for extracting pieces of film from an open end receptacle is shown and described in U.S. Patent 2,811,352 issued to W. Bornemann on October 29, 1957.

From the foregoing description, it is evident that a device has been provided which automatically withdraws a piece of film from an open end receptacle and positions the piece of film in the aperture of a card. Further, the device is completely automatic in that a complete cycle of operation is initiated merely by insertion of the card which is to receive the piece of film upon insertion into the mounting station. Further, controls are provided to arrest the cycle of operation if no film is available in the receptacle for positioning in the card aperture. The embodiment shown and described relates particularly to a card provided with two spaced strips of adhesive material for retaining the piece of film in the card aperture. However, the device is also applicable to a card having a frame of adhesive material for retaining the piece of film and in this particular instance the plunger head would have to be of a size such that it can be moved through the aperture in the frame for contacting the piece of film in the receptacle 24. A second set of rollers would then have to be provided to engage the opposite edges of the film engaged by the rollers 69 and 70 and would, of course, have to be operated in proper timed relationship to the actuation of the rollers 69 and 70. Aside from this difference, the cycle of operation would be exactly the same as described above with respect to the single set of rollers. In order to increase the tackiness of the adhesive material on the card, a simple heating element can be arranged about the aperture in the plate 31, preferably on the underside, to heat said plate so the heat is transferred to the adhesive material as the card lies in the mounting station 30. By this means, the effectiveness of the rollers could be materially increased.

Since other modifications and changes in the described embodiment of the invention could be made by those skilled in the art, it is to be understood that the invention is not to be limited to the disclosure shown and described but is of a scope as defined by the appended claims.

Having now particularly described our invention what we desire to secure by Letters Patent of the United States and what we claim is:

1. In a device for mounting a piece of film in an aperture provided in a card having an adhesive material exposed within said aperture for retaining said piece of film, the combination comprising a mounting station provided with an opening aligned with the aperture in said card, when said card is positioned in said station, an open end receptacle arranged over said mounting station and in alignment with said opening for retaining a stack of

pieces of film in superposed relation, means arranged below said mounting station and movable in one direction to pass through said opening and said aperture to engage the lowermost piece of the film in said receptacle and movable in the other direction to withdraw said piece of film from said receptacle and position it in said aperture, means actuated by said movable means, upon movement in said other direction, for movement from an inoperative position to a position in said mounting station and into contact with the piece of said film in said aperture for urging the piece of film into intimate contact with said adhesive material, and means responsive to a card positioned in said mounting station for initiating movement of said movable means.

15 2. A device in accordance with claim 1 wherein the piece of film is withdrawn from the receptacle and retained on said movable means by means of a vacuum applied to said movable means at the time of movement in said other direction.

20 3. A device in accordance with claim 1 wherein said movable means includes two independent members movable as a unit in the one direction and in the other direction until the piece of film is positioned in the aperture at which time one of said members supports the piece of film in said aperture and the other member continues movement in the other direction for actuating said urging means.

25 4. A device in accordance with claim 1 wherein said movable means includes two aligned and abutting members and resilient means connecting said members for movement as a unit in the one direction and in the other direction until the piece of film is positioned in said aperture at which time one of said members supports said piece of film in said aperture and the other member continues movement in the other direction against the action of said resilient means for actuating said urging means, said resilient means returning said other member in said one direction independently of said one member and into engagement therewith.

30 5. In a device for mounting a piece of film in an aperture provided in a card having an adhesive material exposed within said aperture for retaining said piece of film, the combination comprising a mounting station provided with an opening aligned with the aperture in said card, when said card is positioned in said station, an open-end receptacle arranged over said mounting station and in alignment with said opening for retaining a stack of pieces of film in superposed relation, reciprocative means arranged below said mounting station and movable from a normal position in one direction to pass through said opening and said aperture to engage the lowermost piece of film in said receptacle and in the other direction to withdraw the piece of film from said receptacle and position it in said aperture, means actuated by said reciprocative means, upon movement in said other direction and after said piece of film is positioned in said aperture, for movement from an inoperative position to a position in said mounting station and into contact with the piece of film in said aperture for urging the piece of film into intimate contact with said adhesive material, vacuum means operatively connected to said reciprocative means at the time the piece of film in said receptacle is engaged thereby, means operatively connected to said reciprocative means for moving said reciprocative means in said one and said other direction, and means responsive to a card positioned in said mounting station for initiating said moving means.

35 6. In a device for mounting a piece of film in an aperture provided in a card having an adhesive material exposed within said aperture for retaining said piece of film, the combination comprising a mounting station provided with an opening aligned with the aperture in said card, when said card is positioned in said station, an open-end receptacle arranged over said mounting station and in alignment with said opening for retaining a stack

of pieces of film in superposed relation, reciprocative means arranged below said mounting station and movable from a normal position in one direction to pass through said opening and said aperture to engage the lowermost piece of film in said receptacle and in the other direction to withdraw the piece of film from said receptacle and position it in said aperture, means actuated by said reciprocative means, upon movement in said other direction and after said piece of film is positioned in said aperture, for movement from an inoperative position to a position in said mounting station and into contact with the piece of film in said aperture for urging the piece of film into intimate contact with said adhesive material, means operatively connected to said reciprocative means in said one and said other directions, vacuum means connected to said reciprocative means and to said moving means, control means actuated by said reciprocative means for sequentially applying said vacuum means to said moving means to establish the directions of movement and to said reciprocative means to withdraw the piece of film from said receptacle, and means responsive to a card positioned in said mounting station for initiating said control means.

7. A device in accordance with claim 6 including means responsive to the absence of a piece of film in said receptacle for inhibiting said control means.

8. A device in accordance with claim 6 wherein said means for moving said reciprocative means comprises a vacuum actuated piston operatively connected to a pivotally mounted rocker arm.

9. A device in accordance with claim 6 wherein said reciprocative means includes two aligned and abutting

members and resilient means connecting said members for movement as a unit in the one direction and in the other direction until the piece of film is positioned in said aperture at which time one of said members supports said piece of film in said aperture and the other member continues movement in the other direction against the action of said resilient means for actuating said urging means, said resilient means returning said other member in said one direction independently of said one member and into engagement therewith.

10. A device in accordance with claim 6 wherein said urging means includes a pair of spaced rollers rotatably mounted on a pivotally mounted arm actuated by said reciprocative means.

11. A device in accordance with claim 6 wherein said control means includes a plurality of switches corresponding to the position of said reciprocative means when immediately below said mounting station, the position of said reciprocative means when engaging the lowermost piece of film in said receptacle, and the position of said reciprocative means when said urging means is in said mounting station and has moved over the piece of film in said aperture, said switches being actuated by cams carried by said reciprocative moving means.

12. A device in accordance with claim 6 wherein said control means including an electrical circuit comprising interlocking relays and control valves interconnected with said vacuum means, said reciprocative moving means and said reciprocative means.
